UNITED STATES PATENT OFFICE

2,493,723

POWDER DISTRIBUTOR

George E. Lynn, Midland, Mich., assignor to The Dow Chemical Company, Midland, Mich., a corporation of Delaware

Application August 6, 1945, Serial No. 609,241

1 Claim. (Cl. 43—147)

1
This invention relates to powder distributors and is particularly concerned with an improved and simplified hand-duster adapted to be employed for the application of insecticidal, germicidal, and fungicidal dusts, and other powders.

It is an object of the present invention to provide an improved duster for the distribution of powders. It is a further object to supply a such article of simple construction and low initial cost and adapted to be manually operated with a minimum of exertion. An additional object is to supply a small hand-duster of such design that it may be employed for the successive application of an assortment of dust compositions without the cleaning or dismantling of the operative structure. Other objects will be evident from the present drawings, specification, and claim.

The invention provides an improved powder distributor in the form of a hand-duster of simplified design. This duster comprises a collapsible sidewall disposed between two rigid end plates to form an air chest and bellows. The preferred form of the bellows is tubular although not necessarily. A convenient mode of construction consists of a seamless tube of flexible and collapsible plastic film, the ends of which are fastened to the end plates by detachable ring clamps. This permits the ready replacement of the bellows sidewall.

The bellows assembly includes an air-intake port or ports with check valve and an air-outlet port. A check valve on the outlet port is optional. Conveniently, although not necessarily, the air-intake and outlet ports are positioned in opposing end plates of the bellows structure, and the orifice of the inlet port is substantially greater than that of the outlet port. Also, the end plate opposed to that including the air-outlet port has a suitable handle or bail.

The air-outlet port opens into an air-discharge tube attached to and extending outwardly from an end plate of the bellows. The length of this tube is such as to open into the throat of a dust container attached to the assemblage as herein-after shown. Concentric to this air-discharge tube and of greater diameter is a handhold tube attached to the end plate. The handhold tube is spaced from the air-discharge tube to form a mixing chamber. The outer end of the handhold tube opens into and is adapted detachably to engage a dust container. Thus, there may be positioned around the open end of the handhold tube a screw cap or plate by which a bottle or other dust container may be attached or clamped to the assembly, or the open end of the tube may

be encompassed by a cork or rubber stopper of suitable size to engage the mouth of the dust container.

Attached to and opening out of the mixing chamber provided by the handhold tube, and preferably adjacent to the point of attachment of the latter tube with the bellows end plate, is a delivery tube through which the ultimate air-dust mixture is expelled from the device. Either rigid or flexible tubes or nozzle devices may be attached to the end of the delivery tube.

One manner of construction of the device according to the present invention is illustrated in the appended drawings in which Figure 1 is a perspective view in side elevation of the hand-duster with dust container attached. Figure 2 is a sectional view extending longitudinally and centrally through the duster on the plane indicated by the line 2—2 of Figure 1. Corresponding and like parts are referred to in the following description, and designated in the figures of the drawing by similar reference characters.

Referring to the drawings, a tubular collapsible wall 7 is disposed between two circular and rigid end plates 1 and 10 and fastened thereto by detachable ring clamps 6 to form a bellows and air chest 8. The end plate 1 includes a suitable handle or bail 2 and air-intake ports 3 opening into the air chest of the bellows 8. A rubber flap check valve 5 is positioned over the air-intake ports 3 and held firmly to the end plate 1 by a rivet 4. An air-outlet port 9 opens through the end plate 10 into an air-discharge tube 11 extending outwardly from the end plate 10 and into the throat of a dust container 15. Concentric to this air-discharge tube 11 is a handhold tube 13 attached to the end plate 10 and of greater diameter than the air-discharge tube 11. The tube 13 is spaced from tube 11 to form an air-dust mixing chamber 12, the outer wall of which provides a means for holding the duster. A screw cap 14 is positioned around the open end of the handhold tube 13 and engages a threaded top formed on the dust container 15. Entering the mixing chamber 12 and attached to the handhold tube 13 at a point adjacent to the point of attachment of the latter with the end plate 10 is a delivery tube 16 through which the air-dust mixture is expelled.

In operation, the dust container 15 is filled with a suitable quantity of dust and engaged to the assembly by the screw cap 14. The operator takes the handhold tube 13 in one hand and the handle 2 in the other, directs the delivery tube 16, or an extension thereof, in the direction of the sur-

face or object to be dusted, and pumps the bellows 8. Air passes into the air chest by way of the air-inlet ports 3 and is expelled through the air-outlet port 9 by way of the air-discharge tube 11 into the dust container 15. This causes the dust to be suspended in the air stream and to move into the mixing chamber 12 at such a velocity as to cause turbulent flow and accomplish thorough mixing of the air and dust. The homogeneous air-dust mixture is then expelled through the delivery tube 16.

When it is desired to change dust compositions, all that is required is to disengage the dust container 15 and substitute therefor a container filled with a different dust material. To cleanse the bellows and air discharge tube of the duster, it is sufficient to pump the bellows several times before attaching a new dust container.

The bellows sidewalls 7 may be constructed of leather, rubber, flexible plastic film, canvas, or treated cloth, and are not necessarily completely impervious to air. The end plates 1 and 10 may be of metal, wood, plastic, or any other rigid material. The several tubes 11, 13, and 16 are preferably of rigid construction and may be made of metal, plastic, wood, glass, heavy papier-mâché, etc. The foregoing materials may also be employed in the structure of the dust container, it being necessary only that the latter be of a nature to confine the dust product, withstand the very moderate pressure developed during the dusting operation, and be detachably engageable with the open end of the handheld tube.

Particular advantages of the present duster include the features of ease of operation and 35 excellence of performance. Most devices of this nature function by means of a manually operated plunger type pump delivering an inadequate and intermittent flow of air which results in the ejection of the treating powder in spurts and 40 without being dispersed in the air stream. The present powder distributor combines (1) a bel-

5
10

lows operating with a minimum of exertion to deliver a large volume of air with (2) a mixing chamber in which the dust is dispersed in air by the turbulent flow of the air stream. The result is to produce a drifting cloud of dust particles which settle over a considerable area to give a uniform deposit over plant and other surfaces. The further feature of having the dust container, mixing chamber, and delivery tube positioned outside the bellows assembly provides for a minimum of difficulty in changing from one dust composition to another and in cleansing the apparatus.

I claim:

15 A powder duster comprising a bellows having end plates, an air-intake port with a check valve and a handle on one of said end plates, an air-discharge tube extending axially from the other end plate, an outer tube of larger diameter secured to said other end plate concentrically enclosing in spaced relation said air-discharge tube and defining therewith a mixing chamber, said outer tube being adapted to serve also as a handle; a cap secured to the open end of said outer tube adapted to engage a coupling of a powder container, and a delivery tube laterally projecting from said outer tube.
